his Attorney.

UNITED STATES PATENT OFFICE.

JOHN I. LEMPERA, OF CHICAGO, ILLINOIS.

METALLIC DOOR.

1,021,053.

Specification of Letters Patent. Patented Mar. 26, 1912.

Application filed June 12, 1911. Serial No. 632,712.

To all whom it may concern:

Be it known that I, JOHN I. LEMPERA, a citizen of the United States, and a resident of the city of Chicago, county of Cook, and State of Illinois, have invented certain new and useful Improvements in Metallic Doors, of which the following is a specification.

My invention relates to improvements in metallic doors, the object of the invention being to provide a door of this type which shall be practically devoid of exposed seams and composed of a minimum number of parts.

15 A further object of my invention is to provide a metallic door in which is incorporated adequate fire-resisting materials, thereby rendering the same fire-proof.

Other objects will appear hereinafter.

20 With these objects in view my invention consists in the novel construction and arrangements of parts hereinafter described and claimed.

My invention will be best understood by reference to the accompanying drawings forming a part of this specification, and in which,

25 Figure 1 is a side elevation of a metallic door embodying my invention, Fig. 2 is a vertical longitudinal section thereof taken on line $x-x$ of Fig. 1, Fig. 3 is a detail perspective view showing a plate employed in my invention; Fig. 4 is a transverse horizontal section taken on line $y-y$ of Fig. 1, and Fig. 5 is a similar section taken on line $z-z$ of Fig. 1.

The preferred form of construction of my invention as illustrated in the accompanying drawings comprises a metallic door the parts of which are all composed of sheet metal, thereby rendering the construction thereof cheap, strong, and fire-resisting to a certain degree. Hollow stiles 1 constitute the vertical edges of the door, and the same are connected at their ends by a pair of hollow rails 2 and adjacent their centers by a hollow rail 3. Each stile 1 has a cross section as clearly illustrated in Figs. 4 and 5, the upper and lower end of each stile being inclosed by metal plates 4 which are inserted in the ends of said stiles and suitably secured in position as by soldering. The location of the plates 4 is indicated by horizontal dotted lines in Fig. 1 at the tops and bottoms of the stiles 1 and the object thereof

is clearly to simply close the openings at the ends of each stile. Formed at the inner edge of each stile 1 is a pair of inwardly extending U-shaped channels 5, the inner edges of the rails 2 and both edges of the rails 3 being also provided with channels 5. Formed at each end of the rails 2 and 3 are inwardly extending flanges 6 which are securely engaged with the channels 5 as clearly illustrated in Fig. 5. It is apparent that the flanges 6 of the rails 2 and 3 must be engaged with the channels 5 during the forming of the edges of the same. After the rails are once formed and the flanges 6 engaged with the channels 5 then the walls 70 at the edges of said rails will lock said flanges with said channels, no further locking means being necessary.

By reference to Fig. 5 it will be seen that the inner edges of the channels 5 are spaced apart. The object of this spacing is to form a slot for the insertion of a hollow metallic panel 7 the thickness of which corresponds substantially with the width of said slot. Each panel 7 is inserted in the slots of the 80 stiles and rails provided therefor and locked in position by means of sheet metal moldings 8 as will be presently described. Each panel 7 is provided with a filling of asbestos 9 or other fire-resisting material, and 85 each stile and rail is provided with longitudinal strips 10 of asbestos or other fire-resisting material arranged diagonally therein and extending the entire length thereof. The object of the diagonal arrangement of the strips 10 is to divide the 90 stiles and rails into two separate air compartments, it being well known that still air is an effecting insulator in itself. A molding 8 comprises an edge 11 which abuts 95 one side of a panel 7. The molding extends from the edge 11 in the direction of a corner of one of the inner edges of a stile or rail, thence inwardly to the bottom of a channel 5, thence after being bent upon 100 itself the same extends out of said channel and around the same whereupon it terminates in one of the walls of said panel which is formed integral therewith. This construction of one set of the moldings 8, 105 is clear by reference to Figs. 2 and 4. Another set of moldings 8 similar to that just described is shown in Figs. 2 and 4. These moldings form a seat for the panels 7 and prior to terminating in a wall of a panel 110

7 as do the moldings above described they inclose the edges of said panels as will be seen.

When the rails, stiles and panels are 5 turned together and securely locked, a very stiff and durable door is obtained. And when the door is finished and enameled the seams in the stiles and rails are invisible, and the enamel is not likely to crack at these 10 points.

It is apparent from the foregoing description that window sashes and other like objects can be constructed according to this 15 invention, since the drawings forming a part of this specification are only intended to illustrate one application thereof.

A metallic door of the construction set forth is simple of construction, cheap to manufacture and neat and compact in appearance.

While I have illustrated and described the preferred form of construction for carrying my invention into effect, this is capable of variation and modification without departing from the spirit of my invention. I, therefore, do not wish to be limited to the precise details of construction as set forth, but desire to avail myself of such variations and modifications as come within the scope 30 of the appended claims.

Having described my invention what I claim as new and desire to secure by Letters Patent is:

1. A metallic door comprising a pair of 35 hollow stiles, a plurality of hollow rails connecting said stiles and disposed perpendicular thereto, there being inwardly turned U-shaped channels at the inner edges of said stiles and correspondingly formed flanges 40 formed at the ends of said rails, hollow panels connecting said stiles and rails, and hollow metallic moldings reinforcing the connection of said panels with said stiles and rails comprising a portion extending from 45 the face of the panel toward a corner of one of said stiles, thence inwardly in a channel, thence after being bent upon itself out of 50 said channel and around the same terminating in one side of said panel which is formed integral therewith, substantially as described.

2. A metallic door comprising a pair of elongated hollow stiles formed of sheet metal, a strip of fire resisting material extending the entire length of each of said 55 stiles and arranged diagonally therein, a plurality of hollow rails formed of sheet metal and connecting said stiles, each rail being provided with a strip of fire resisting material which is substantially co-extensive therewith and arranged diagonally therein, 60 hollow panels and hollow moldings integrally formed therewith surrounded by said stiles and rails and connected thereto, said moldings comprising a portion extending 65 from the face of the panel toward a corner of one of said stiles, thence inwardly in a channel, thence after being bent upon itself out of said channel and around the same terminating in one side of said panel integrally 70 formed therewith, and a filling of fire resisting material in said panels, substantially as described.

3. A metallic door comprising a pair of elongated hollow stiles formed of sheet metal, a strip of fire resisting material extending the entire length of each of said 75 stiles and arranged diagonally therein, a plurality of hollow rails formed of sheet metal and connecting said stiles, each rail being provided with a strip of fire resisting material which is substantially co-extensive therewith and arranged diagonally therein, 80 hollow panels and hollow moldings integrally formed therewith surrounded by said stiles and rails and connected thereto, said moldings comprising a portion extending from the face of the panel toward a corner of one of said stiles, thence inwardly in a channel, thence after being bent upon itself 85 out of said channel and around the same terminating in one side of said panel integrally formed therewith, and a filling of asbestos in said panels, substantially as described.

In testimony whereof I have signed my name to this specification in the presence of two subscribing witnesses.

JOHN I. LEMPERA.
